UNITED STATES PATENT OFFICE

114,668

DESIGN FOR A COMBINED CLOCK AND SMOKING STAND

James Madison Walkley, Akron, Ohio, assignor of twenty-five per cent to James W. Shelton, twenty-five per cent to Richard P. Kelley, and fifteen per cent to Edward Heichelbech, Akron, Ohio

Application December 22, 1938, Serial No. 81,948

Term of patent 3½ years

To all whom it may concern:

Be it known that I, James Madison Walkley, a citizen of the United States, residing at Akron, in the county of Summit and State of Ohio, have invented a new, original, and ornamental Design for a Combined Clock and Smoking Stand, of which the following is a specification, reference being had to the accompanying drawing, forming part thereof.

I claim:

The ornamental design for a combined clock and smoking stand, as shown.

JAMES MADISON WALKLEY.
